BRUSH ASSEMBLY

Ruben O. Peterson, University Heights, Ohio, assignor to
The Osborn Manufacturing Company, Cleveland, Ohio,
a corporation of Ohio

Application November 10, 1950, Serial No. 195,011

3 Claims. (Cl. 15—77)

This invention relates as indicated to a novel brush assembly and, more particularly, to brushes utilizing special holders for retaining lengths of brush strip therein.

In my prior Patent No. 2,303,386 I disclose a novel form of brush strip adapted to be produced in continuous lengths comprising a metal channel form back with stranded brush material doubled about a longitudinally extending retaining wire secured therein by teeth punched in from the sides of such back. Brush strip of this sort may be circularized, helically or otherwise, or cut into desired lengths for insertion in appropriate brush backs or holders. The ends of the severed channel form back of the length of brush strip will preferably be pinched together to prevent loss of any of the brush material which is, however, a minor problem with this type of brush strip since such material is firmly secured in the channel back by the retaining wire and teeth.

A variety of different forms of holders have been proposed in the past for securing brush strip, either temporarily or permanently, in appropriate holders or for mounting the same on hubs or the like. In general, these have been characterized by various problems of assembly and disassembly and also, in many cases, by a tendency for the parts to work loose under the effect of vibratory action in use. Particularly in the case of long lead helical brushes and other rotary brushes having brush strip extending axially thereof there has been considerable trouble involved in replacing worn brush elements. Where relatively straight lengths of brush strip have been seated in rotary mounting means by axial insertion of the back of such strip in a solid grooved support, considerable frictional resistance is met with in thus inserting the strip and later withdrawing the same for replacement. Furthermore, it has been difficult to afford sufficient ventilation to brush assemblies of this latter type.

It is accordingly a primary object of my invention to provide a novel brush assembly wherein lengths of brush strip may be inserted with a minimum of difficulty but which strip will then be firmly seated and secured in use.

Another object is to provide such brush assembly wherefrom such lengths of brush strip may readily be withdrawn for replacement when worn or when a different type of brushing action is desired.

Still another object is to provide a rotary brush assembly including a central supporting structure on which lengths of brush strip may be seated and secured extending in a direction generally parallel to the axis of such support, such lengths of brush strip being either straight or of long lead helical conformation.

Other objects of my invention will appear as the description proceeds.

To the accomplishment of the foregoing and related ends, said invention then comprises the features herein-after fully described and particularly pointed out in the claims, the following description and the annexed drawing setting forth in detail certain illustrative embodiments of the invention, these being indicative, however,

2

of but a few of the various ways in which the principle of the invention may be employed.

In said annexed drawing:

Fig. 1 is a side elevational view of two specially formed rotary brushes embodying the principle of my invention adapted to operate in complementary fashion upon an interposed work-piece;

Fig. 2 is a fragmentary longitudinal sectional view through the right-hand end portion of the upper brush of Fig. 1;

Fig. 3 is a similar sectional view of the right-hand end portion of the lower brush shown in Fig. 1;

Fig. 4 is a fragmentary transverse sectional view taken on the line 4—4 on Fig. 2;

Fig. 5 is a sectional view taken on the line 5—5 on Fig. 1.

Referring now more particularly to Figs. 1 to 5 of the drawing, the embodiment of my invention there illustrated is indicative of the manner in which my new brush assembly may be modified to conform to unusual shapes and work surfaces. The particular embodiment illustrated is designed simultaneously to brush both sides of a curved automotive windshield, but it will be appreciated that the precise shape of the brush or brushes will be governed by the special operation for which they are intended. In the past, when an attempt has been made to provide a rotary brush of special contour, this has almost always been done by trimming the brush material accordingly. For many operations such brushes have proven quite unsatisfactory due principally to the fact that since the brush material extends different distances from the support or retaining means the brushing characteristics of different portions of the brush are likewise widely different. Ordinarily, for example, relatively shorter bristles will have a stronger and sharper brushing action than longer bristles of the same material.

The upper brush shown in Fig. 1 comprises a tubular core 48 having stub shaft bearing members 49 and 50 press fitted within the respective ends of the same. Such stub shaft members may additionally be welded or otherwise secured to core 48 if desired. A plurality of annular sheet metal discs 51, 52 and 53 are mounted on such core and welded in place, such discs being notched at spaced points about their peripheries to receive channel-form brush strip retaining elements 5 which are welded in place in such notches. As shown in Fig. 1, such notches and retaining members may be disposed in longitudinal alignments parallel to the axis of core 48 and the supporting discs carried by the latter so that lengths of brush strip inserted therein will likewise lie in planes radially of such core. The endmost discs 54 and 55, instead of being of sheet metal, may be substantially thicker than the other discs and notched to receive the channelform backs 9 of the brush strip directly therein as shown in Figs. 2 and 4. The end portions of the brush strip retained in such notches are secured in place by means of conical headed screws 56 inserted in such discs with their heads overlying the edges of the brush strip channel backs 9.

Retaining members 5 and the notches or grooves in end members 54 and 55 will be inclined, as shown, to support the lengths of brush strip at the desired angle (portions of the brushes of Fig. 1 are, of course, broken away better to illustrate the internal construction of the assembly). It will thus be seen that a rotary brush assembly has been provided which, while of generally cylindrical form, has nevertheless been modified so that the over-all diameter of the brush varies considerably from end to end without, however, any change in the length of brush material 10 extending from the individual brush strip backs 9.

In the embodiment illustrated in Fig. 1, a second rotary

brush is provided having an axially concave contour adapted to complement the axial convex contour of the brush just described, so that both sides of a curved automotive windshield passed therebetween may be brushed simultaneously. Such concave brush likewise comprises a tubular hub or core member 57 having stub shaft bearing members 58 and 59 press fitted in the respective ends thereof. A plurality of annular sheet metal discs 60, 61, 62, 63 and 64 are welded on such core 57 and notched at their peripheries to receive channel retaining members 5 in which the backs 9 of the lengths of brush strip are received. Such retaining members 5 will be welded to the discs at the proper angles to secure the desired brush contour as shown.

The lengths of brush strip thus employed in these two cooperating brush assemblies will preferably be preformed to approximately the desired curvature before being axially inserted in the alignment of strip retaining members 5. Obviously, the notches in the discs may be so disposed and the retaining members welded therein shaped to receive lengths of brush strip also formed with a long lead helix, if desired.

End plates may be provided to prevent axial displacement of the lengths of brush strip in use, although the same will not always be necessary. As shown in Fig. 5, pins 65 are inserted through corresponding apertures in the sides of members 5 to overlie the edges of the channel-form brush back 9 to secure the latter in place. Such pins will also obviously serve to prevent axial withdrawal of the length of brush strip from the retaining members. The ends of the pins may be slightly upset to ensure that they will not become displaced. A variety of brush constructions utilizing alignments of my new retaining members 5 to carry the replaceable lengths of brush strip will be obvious to those skilled in the art.

The brush strip employed will preferably be of the type described above, but any commercially available brush strip comprising an elongated back from which a layer of brush material extends may be utilized. The terms "brush" and "brush strip" as used herein are intended to include buffing as well as strictly brushing materials. Thus, suitable materials for various uses include tampico fiber, wire, horsehair, synthetic plastic strands such as nylon, and buff fabrics such as cotton cloth.

This application is a continuation-in-part of my co-pending application Serial No. 81,985, filed March 17, 1949, now Patent No. 2,658,315 granted November 10, 1953.

It will be seen that I have provided means whereby rotary brushes having relatively complex contours may readily be assembled without the necessity of a difficult trimming operation to be performed on the assembled brush. Not only may the brush material of the brush strip be trimmed to desired length prior to assembly but also, since the length of trim is ordinarily uniform, substantially uniform brushing characteristics are obtained for the entire brush face. Whether the finished brush is to have a longitudinally concave, convex, or tapered contour the lengths of brush strip may be mounted in their normal straight form or may be in the form of long lead helices as above described. The alignments of axially spaced channel members which support and secure the lengths of brush strip maintain the desired conformation of the latter while at the same time facilitating insertion and replacement. The whole construction is, of course, quite light in weight and facilitates the feeding of fluids such as air or water, for cooling, or powdered abrasives, for example, to the working face of the brush. Similarly, suction may be applied to withdraw surface dirt and the like, if desired.

Other modes of applying the principle of the invention may be employed, change being made as regards the details described, provided the features stated in any of the following claims or the equivalent of such be employed.

I therefore particularly point out and distinctly claim as my invention:

1. In combination, a generally cylindrical rotary brush comprising an arbor, a plurality of axially spaced discs mounted thereon for rotation therewith, rigid sheet metal channel members individually secured to the outer peripheries of said discs and extending generally parallel to said arbor, thereby forming a plurality of circumferentially arranged generally axially extending alignments of said channel members, lengths of brush strip inserted in said channel members of such respective alignments, said brush strip comprising an elongated back portion with brush material of uniform trim retained therein and extending therefrom, said brush strip back portion being seated in said channel members, means overlying the side edges of said backs of said lengths of brush strip to prevent escape of the same, intermediate ones of said discs being of less diameter than the endmost of said discs whereby the longitudinal profile of said brush is of concave contour; and a closely opposed generally cylindrical brush of complementary convex profile having an arbor parallel to the arbor of said first brush, a plurality of axially spaced discs mounted thereon for rotation therewith, rigid sheet metal channel members individually secured to the outer peripheries of said discs and extending generally parallel to said arbor, thereby forming a plurality of circumferentially arranged generally axially extending alignments of said channel members, endmost discs of greater thickness but less diameter than the aforesaid discs mounted on said arbor for rotation therewith, said endmost discs having notches in their outer peripheries aligned with such respective alignments of said channel members, lengths of brush strip inserted in said channel members of such respective alignments, said brush strip comprising an elongated back portion with brush material of uniform trim retained therein and extending therefrom, and means overlying the side edges of said backs of said lengths of brush strip to prevent escape of the same from said aligned channel members and notches.
2. In combination, two generally cylindrical rotary brushes having parallel arbors, one said brush having a longitudinally concave contour and the other said brush having an opposed complementary longitudinally convex contour, each said brush comprising a plurality of axially spaced annular discs mounted on a central arbor, sheet metal channel members secured to the outer peripheries of said discs and extending generally parallel to said arbor in a series of circumferentially arranged generally axially extending alignments, lengths of brush strip inserted in said channel members of such respective alignments, said brush strip comprising an elongated back portion with brush material of uniform length of trim retained therein and extending therefrom, and means overlying the side edges of said back portions of said lengths of brush strip adapted to prevent escape of the latter from said channel members in use, the diameters of said respective discs being selected to afford the desired longitudinal contour of the brush.
3. A rotary brush comprising an arbor, a plurality of axially spaced annular discs of different diameters mounted thereon for rotation therewith, axially spaced sheet metal channel members secured to said discs and forming a series of circumferentially arranged alignments extending generally longitudinally of the brush assembly, said channel members opening radially outwardly and being axially spaced from one another in each such alignment, lengths of brush strip inserted in said channel members of such respective alignments, said brush strip comprising an elongated back portion with brush material of uniform length of trim retained therein and extending therefrom, and pins extending transversely through the side walls of said channel members and penetrating said brush material, said pins overlying the side edges of said back portions of said lengths of brush strip adapted to prevent escape of the latter from said channel members

in use, the diameters of said respective discs being selected to afford the desired longitudinal contour of the brush.
